(57) **CLAIM**

The ornamental design for a weigh-in-motion apparatus, as shown and described.

DESCRIPTION

3. Weigh-in-motion apparatus

FIG. 3.1 is a front elevation view thereof;

FIG. 3.2 is a rear elevation view thereof;

FIG. 3.3 is a right side elevation view thereof;

FIG. 3.4 is a left side elevation view thereof;

FIG. 3.5 is a top plan view thereof;

FIG. 3.6 is a bottom plan view thereof;

FIG. 3.7 is a perspective view of a weigh-in-motion apparatus embodying the new design from above the front left side thereof; and

FIG. 3.8 is a perspective view from below the rear right side thereof.

The break lines in the drawings indicate that the appearance of any portion of the weigh-in-motion apparatus between the break lines forms no part of the claimed design.

The broken lines in the reproductions illustrate portions of the weigh-in-motion apparatus that form no part of the claimed design.
